UNITED STATES PATENT OFFICE.

MARTIN S. RUNSVOLD, OF SAN DIEGO, CALIFORNIA.

AUTOMATIC ELECTRIC FLATIRON.

Application filed August 11, 1924. Serial No. 731,314.

To all whom it may concern:

Be it known that I, MARTIN S. RUNSVOLD, a citizen of the United States, residing at San Diego, in the county of San Diego and 5 State of California, have invented a certain new and useful Automatic Electric Flatiron, of which the following is a specification.

My invention relates to automatic electric flat irons, and the objects of my invention 10 are: first, to provide an automatic electric flat iron in which the contact of the switch members of the switch mechanism or contact means connecting the heating elements of the iron with a source of electrical energy is automatically and quickly broken when the iron is heated to a certain predetermined 15 high temperature; second, to provide a novelly constructed thermostatic switch mechanism for heating apparatus whereby the 20 electric connection between the heating elements of the heating apparatus and the source of electrical energy is suddenly broken; third, to provide a thermostatic switch mechanism of this class which consists primarily of a pair of mutually 25 shiftable resilient members adapted to be suddenly shifted in one direction for quickly breaking an electrical contact when the heat 30 in the heating apparatus, with which the switch mechanism is used, is heated to a certain predetermined high temperature; fourth, to provide a switch mechanism of 35 this class which is provided with a pair of shiftable thermostat members adapted to be distorted by heat and suddenly shifted when the thermostat members are heated to a certain temperature; fifth, to provide a novel 40 means for adjusting the switch mechanism so that the same will be actuated at substantially the specific temperature desired; sixth, to provide a novelly constructed 45 thermostatic switch mechanism; seventh, to provide a novelly constructed casing for electric flat irons, and eighth, to provide an automatic electric flat iron which is very 50 simple and economical of construction proportionate to its functions, durable, efficient, easy to adjust and operate, and which will not readily deteriorate or get out of order.

With these and other objects in view, as will appear hereinafter, my invention consists of certain novel features of construction, combination and arrangement of parts and portions, as will be hereinafter de-

scribed in detail and particularly set forth 55 in the appended claims, reference being had to the accompanying drawings and to the characters of reference thereon, which form a part of this application, in which:

Figure 1 is a plan view of my electric 60 flat iron, with the casing and other members partly broken away and in section to facilitate the illustration; Fig. 2 is a side elevational view thereof, with the casing, base 65 plate and other members partly broken away and in section, to facilitate the illustration; Fig. 3 is a bottom view of the removable thermostatic switch unit adapted to be positioned within the casing of the iron; Fig. 4 is a fragmentary transverse sectional 70 elevational view of my flat iron, with the section taken through 4-4 of Fig. 2; Fig. 5 is a fragmentary rear elevational view of my 75 flat iron; Fig. 6 is a fragmentary sectional elevational view of the thermostatic switch unit thereof, with the section taken through 6-6 of Fig. 1, and Fig. 7 is a sectional elevational view thereof, with the section taken through 7-7 of Fig. 2.

Like characters of reference refer to similar parts and portions throughout the several views of the drawings.

The base plate 1, heating unit 2, main 80 casing 3, handle supporting member 4, handle 5, top plate 6, stud 7, screw 8, thermostatic switch mechanism supporting member 9, screw 10, nuts 11, pivotal thermostat member support 12, thermostat member 13, rivet 14, adjustable thermostat member 15, rivets 16, adjustable thermostat member support 17, adjusting cam member 18, adjusting rod 19, adjusting button 20, terminal posts 21, terminal post protecting member 22, conductor bar 23, screw 24, conductor 25, bolt 26, stationary switch members 27, pivotal 85 switch member 28, conductor 29, screw 30, and the terminal post protecting member 90 clip 31, constitute the principal parts and portions of my automatic flat iron structure.

The base plate 1, the heating unit 2 consisting of the heating elements 2^a and the insulating material 2^b, the main casing 3, the handle supporting member 4, and the handle 5 are similar in construction to those of conventional flat irons. The top plate 6, positioned within the main casing 3, for securing the heating unit 2 in position to the base plate 1, is provided at the top side of its rear 100 105

portion with a hollowed-out portion 6^a in which is positioned the main portion of the thermostatic switch mechanism. The plate 6 is secured to the plate 1 by means of a 5 stud 7 at its forward portion and by means of a screw 8 at its rear portion.

The thermostatic switch mechanism is assembled as a complete unit on the supporting member 9, the bottom side of the complete unit being shown in Fig. 3. The forward end of the supporting member 9 is secured between the head 7^a of the stud 7 and a boss 6^b at the upper side of the plate 6. The supporting member 9 is positioned 10 and secured at its rear end relatively to the plate 6 by means of a pair of laterally extending arms 9^a at the lower portion of the rear end of the member 9, which arms extend into notches 6^c at the lower portion of the 15 rear end of the plate 6, as shown best in Figs. 2 and 4. The arms 9^a are preferably provided intermediate their ends with offset portions forming shoulders which are positioned against the rear ends of the side walls 20 forming the hollowed-out portion 6^a of the plate 6, to position the supporting member 9 laterally relatively to said plate. The upper portion of this member 9 consists of a plate 9^e which covers substantially the whole 25 of the hollowed-out portion of the plate 6 and is provided at its sides with laterally extending, downwardly curved lugs 9^f which extend over the upper portions of the sides of the plate 6 for vertically positioning the 30 member 9 relatively to said plate.

Intermediate the ends of the plate 9^e of the member 9 is provided a screw 10, which extends upwardly therefrom and is locked in position by means of a nut 10^a. The 35 handle supporting member 4 is secured relatively to the main casing 3 by means of nuts 11 screwed over the ends of the stud 7 and the screw 10 extending above the casing 3.

The supporting member 9 is provided at its rear end and underneath the plate 9^e with a pair of spaced apart, forwardly extending supporting portions 9^b, preferably formed as an integral part with the member 9. At the 40 forward ends of the portions 9^b, of the member 9 is pivotally mounted a pivotal support 12, which extends backwardly therefrom. The pivotal connection between said members consists of substantially 45 V-shaped notched portions 9^c at the forward ends of the portions 9^b, and knife-edge portions 12^a extending laterally from the pivotal support 12 and positioned within the V-shaped notched portions, as 50 shown best in Figs. 3 and 6 of the drawings. The outer or normally forward portions of the notched portions 9^c serve as stops to limit the pivotal movement or high and low 55 positions of the member 12. To the lower side of the rear end of the pivotal support

12 is secured the one end of a curved resilient thermostatic member 13, preferably by means of a lug extending upwardly into a notched portion at the end of the member 12 and by means of a rivet 14. The forward end of the thermostatic member 13 is provided with a knife edge 13^a, which extends into a substantially V-shaped, transversely slotted portion 15^a at the rear end of the adjustable thermostatic member 15 forming a pivotal 60 connection between said members, as shown best in Figs. 3 and 6. The forward end of the thermostatic member 15 is secured, by means of rivets 16, to a transversely extending supporting portion 17^a of the adjustable support 17, which is reciprocally mounted in a downwardly bent guide portion 9^d of the supporting member 9, the adjustable support 17 being secured relatively to the portion 9^d by means of a lug 17^b extending 65 through the longitudinal slot of the guide portion 9^d and bent upwardly therefrom, as shown best in Fig. 7. At the rear end of the adjustable support 17 is provided a laterally bent portion 17^c, which is provided at the lower portion of its forward side with a small lug 17^d, which is engageable by an adjusting cam member 18 secured at the inner end of the adjusting rod 19. This adjusting rod is rotatably mounted at its inner or forward end in the portion 17^c of the adjustable support 17 and at its rear or outer end in the rear wall portion of the supporting member 9. The rear end of the adjusting rod 19 is provided with a button 20 for 70 rotating the cam member 18. The rotation of the cam member 18 will increase or decrease the compression on the adjustable thermostatic member 15 depending upon the direction in which the button 20 is rotated.

At the rear end of the thermostatic switch mechanism supporting member 9 are secured a pair of spaced apart terminal posts 21, which are insulated from the support 9 and extend upwardly therefrom through openings 3^a at the upper side of the rear end of the main casing 3 into the terminal post protecting member 22. The one terminal post 21 is directly connected by means of a conducting bar 23 and a screw 24, with the one 75 end of the electric heating element 2^a. To the other terminal post 21 is secured a semi-rigid conductor 29, which is bent downwardly and forwardly and provided at its forward end with a knife edge against which is positioned the notched or V-shaped portion 28^a at the rear end of the pivotal switch member 28. This switch member 28 is secured intermediate its ends to and insulated 80 from one of the laterally extending lugs 12^a of the pivotal support 12, as shown best in Figs. 2 and 3, the member 28 being secured to said lug 12^a by means of a reduced portion at the end of said lug extending through the member 28 and riveted over at its outer 85

end. The forward end of the pivotal switch member 28, when in the contact position, extends into a recess formed by a pair of stationary switch members 27 secured by means 5 of a bolt 26 to the forward end of a conductor 25 supported by and insulated from the supporting member 9, the opposite end of the conductor 25 being secured by means of a screw 30 to the other end of the heating ele-
 10 ment 2^a of the heating unit of the iron. It will be here noted that the axis of the pivotal connection of the pivotal switch member 28 with the semi-rigid conductor 29 is positioned in alinement with the axis of
 15 the pivotal connection between the forward-
 20 ly extending supporting portions 9^b of the supporting member 9 and the pivotal support 12 for the thermostat member 13, the conductor 29 being sufficiently resilient to provide a continuous force against the V-
 25 shaped portion of the switch member 28 to insure a good contact therewith. The switch member 28 is also preferably provided with an extended lug 28^b, which extends through a slotted portion of the conductor 29 to fur-
 30 ther insure a good contact between the mem-
 bers 28 and 29. It will be noted that the conductor 25 extends forwardly of one of the laterally extending lugs 9^c of the sup-
 35 porting member 9 so that the knife switch members 27 may be readily removed without removing the member 9.

It will be seen from the above that when the iron is heated, the thermostat members 35 13 and 15, being made of pairs of metal plates of different coefficients of expansion, will be distorted downwardly, forcing the pivotal connection between said thermostat members towards the opposite side of the 40 center or dead line connecting the front end of the thermostat member 15 with the pivotal mounting of the thermostat member 13, thus disengaging the pivotal switch mem-
 45 ber 28 from the switch members 27 and breaking the electric circuit of the heating unit of the iron with the source. The action of the thermostat members 13 and 15 relatively to each other and their supports is substantially the same in principle as the 50 action of an over-center spring. As the iron cools, by reason of the electric current being shut off, the thermostat members 13 and 15 automatically assume their original shape or position, forcing the pivotal connection between said members to the oppo-
 55 site side of the dead line connecting the supporting means of the thermostat members. It will be here noted that as the pivotal connection between the thermostat 60 members passes beyond the dead line, the movement is rapid, thus suddenly connecting and breaking the contact between the switch members 27 and 28.

It will also be seen from the above that 65 as the button 20 is turned clockwise, the ad-

justable support 17 is shifted backwardly, increasing the force against or the compression of the thermostat member 15, which tends to hold the pivotal connection between the thermostat members to one side or the other of the dead line, therefore permitting the iron to become hotter before the contact between the switch members 27 and 28 is broken.

The terminal protecting member 22 is 75 provided at its rear side with a backwardly and downwardly extending indicating portion 22^a which is directed toward the button 20. The button 20 is provided with the inscriptions: "H," "M" and "L", signifying respectively high, medium and low heat, and indicating in which direction the button is to be turned relatively to the indicating portion 22^a to obtain the desired heat.

Said member 22 is provided at its lower 85 end with backwardly extending loop portions 22^b upon which the iron is adapted to rest when hot and not using the same, which loop portions are provided at their lower inner ends with lugs 22^c which extend into 90 corresponding slots at the lower portion of the rear side of the main casing 3 and engage the inner wall thereof. The upper end of the member 2 is secured in position against the main casing 3 by means of a 95 slip 31 secured to the back side of the rear portion of the handle supporting member 4, which clip extends over the upper edge of the front portion of the member 22, as shown best in Figs. 2 and 5. Thus, it will 100 be seen that by unscrewing the nuts 11 substantially the whole outer portion of the iron may be disassembled.

It is obvious from this construction, as illustrated in the drawings and disclosed 105 in the foregoing specification, that there is provided an automatic electric flat iron as aimed at and set forth in the objects of the invention, and though I have shown and described a particular construction, 110 combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent, is:

1. In a heating apparatus, a support and a pair of heat controlled, mutually shiftable members supported at their one ends on said support and adapted to be suddenly shifted when shifted beyond a dead line relatively 125 to their means of support.
2. In a heating apparatus, a support, a pair of heat controlled, mutually shiftable members supported at their one ends on said support and adapted to be suddenly shifted 130

when shifted beyond a dead line relatively to their means of support, and a switch member connected to and shiftable with one of said shiftable members.

5. 3. In a heating apparatus, a casing, a support positioned in said casing, and a pair of heat controlled, pivotally connected members supported by said support, the pivotal connection therebetween being adapted to be suddenly shifted to the opposite sides of the line connecting their means of support.

4. In a heating apparatus, a casing, a support positioned in said casing, a pair of heat controlled, pivotally connected members supported by said support, the pivotal connection therebetween being adapted to be suddenly shifted to the opposite sides of the line connecting their means of support, and a switch member connected to and shiftable with one of said pivotally connected members adapted to break and complete an electric circuit of said heating apparatus.

5. In a heating apparatus, a casing, a support positioned in said casing, a pair of heat controlled, pivotally connected members supported by said support, the pivotal connection therebetween being adapted to be suddenly shifted to the opposite sides of the line connecting their means of support, a switch member connected to and shiftable with one of said pivotally connected members adapted to break and complete an electric circuit of said heating apparatus, and a means for adjusting the compression between said pivotally connected members.

6. In a heating apparatus, a casing, an electric heating element positioned therein, a support positioned in said casing, a pair of heat controlled, pivotally connected members supported by said support, the pivotal connection therebetween being adapted to be suddenly shifted to the opposite sides of the line connecting their means of support, terminal posts mounted on said support, stationary switch means connected with the heating element of said heating apparatus, and a movable switch member connected with one of said terminal members and adapted to be connected with said stationary switch means with the shifting of said pivotal members.

7. In a heating apparatus, a casing, a pair of heat controlled, pivotally connected, mutually shiftable switch actuating members positioned within said casing, their pivotal connection being adapted to be suddenly shifted when said members are subjected to heat.

8. In a heating apparatus, a casing, a pair of heat controlled, pivotally connected, mutually shiftable switch actuating members positioned within said casing, their pivotal connection being adapted to be suddenly shifted when said members are subjected to heat, and a means for adjusting the com-

pression of one of said members relatively to the other.

9. In a heating apparatus, a casing, and a pair of pivotally connected, heat distortable thermostat members, positioned within said casing and mutually shiftable relatively to each other.

10. In a heating apparatus, a casing, a pair of pivotally connected, heat distortable thermostat members positioned within said casing and mutually shiftable relatively to each other, the pivotal connection of said thermostat members being adapted to be shifted from one side of a line connecting their supporting means to the other, and a movable switch member connected with one of said thermostat members.

11. In a heating apparatus, a casing, a pair of pivotally connected, heat distortable thermostat members positioned within said casing and mutually shiftable relatively to each other, the pivotal connection of said thermostat members being adapted to be shifted from one side of a line connecting their supporting means to the other, a movable switch member connected with one of said thermostat members, and means for adjusting the compression of said thermostat members relatively to each other.

12. In a heating apparatus, a casing, a heat distortable thermostat member pivotally mounted within said casing, and another heat distortable thermostat member supported at one end within said casing and pivotally connected at its opposite end with the one end of said first mentioned thermostat member.

13. In a heating apparatus, a casing, a heat distortable thermostat member pivotally mounted within said casing, and another heat distortable thermostat member supported at one end within said casing and pivotally connected at its opposite end with the one end of said first mentioned thermostat member, the pivotal connection of said thermostat members being normally positioned at one side of a line connecting the supporting portions of said thermostat members and adapted to be suddenly shifted to the other side of said line when subjected to heat.

14. In a heating apparatus, a casing, a heat distortable thermostat member pivotally mounted within said casing, another heat distortable thermostat member supported at one end within said casing and pivotally connected at its opposite end with the one end of said first mentioned thermostat member, the pivotal connection of said thermostat members being normally positioned at one side of a line connecting the supporting portions of said thermostat members and adapted to be suddenly shifted to the other side of said line when subjected to heat, a stationary switch member positioned

within said casing, and a movable switch member connected with said first mentioned thermostat member and shiftable therewith adapted to engage said first mentioned 5 switch member when said first mentioned thermostat member is in a normal position.

15. In a heating apparatus, a supporting means, and a pair of connected, mutually

shiftable, heat distortable thermostat members supported by said supporting means 10 and adapted to be suddenly shifted when heated beyond a predetermined temperature.

In testimony whereof, I have hereunto set my hand at San Diego, California, this 4th day of August, 1924.

MARTIN S. RUNSVOLD.
